UNITED STATES PATENT OFFICE.

REUBEN B. BENJAMIN, OF CHICAGO, AND WALTER A. ALDEN, OF CAMP GRANT, ROCKFORD, ILLINOIS, ASSIGNEES TO BENJAMIN ELECTRIC MANUFACTURING COMPANY, OF CHICAGO, ILLINOIS, A CORPORATION OF ILLINOIS.

ELECTRICAL CONNECTER DEVICE.

Application filed June 12, 1918. Serial No. 239,518.

To all whom it may concern:

Be it known that we, REUBEN B. BENJAMIN and WALTER A. ALDEN, citizens of the United States, residing, respectively, at Chicago, in the county of Cook and State of Illinois, and Camp Grant, Rockford, Illinois, have invented certain new and useful Improvements in Electrical Connecter Devices, of which the following is a full, clear, 10 concise, and exact description, reference being had to the accompanying drawings, forming a part of this specification.

Our invention relates to electrical connector devices.

One of the objects of our invention is to provide an improved receptacle having a rotatable screw contact device in which the screwing in of the co-operating connecter device will rotate the rotatable contact to connect the receptacle contacts with the supply-circuit. A further object of our invention is to provide a safety receptacle which will be simple in construction, efficient in operation, and durable in use. Further objects 25 will appear from the detailed description to follow and from the appended claims.

In order to give a general idea of the invention, it is here stated that the embodiment shown comprises an Edison receptacle, 30 the shell contact of which is oscillated about its own axis, this oscillation being effected by the screwing in and out of the lamp-base or plug. This oscillation of the screw contact operates a double-pole snap-switch, 35 which switch controls the connection between the feed-wires and the two contacts of the receptacle. The screw shell contact of the receptacle is provided with lamp-grip means, which oscillate with the screw shell 40 contact and which grip the lamp-base or plug and insure the oscillation of the screw shell contact when the lamp-base or plug is screwed out of the receptacle.

In the embodiment shown, the receptacle 45 is of the duplex type, having a receptacle portion of the Edison type and also having a receptacle portion of the quick-detachable type.

In the drawings—

50 Figure 1 is a plan view of a duplex receptacle embodying our invention;

Fig. 2 is a plan view of the receptacle with the upper portion of the base removed;

Fig. 3 is a bottom view of the receptacle; 55 Fig. 4 is a section on the line 4—4 of Fig. 1;

Fig. 5 is a section on the line 5—5 of Fig. 2;

Fig. 6 is a section on the line 6—6 of 60 Fig. 2;

Fig. 7 is a view showing a detail of the switch mechanism;

Fig. 8 is a view from the right of Fig. 7;

Fig. 9 is a perspective view showing the 65 lamp grip;

Fig. 10 is a section on the line 10—10 of Fig. 2;

Fig. 11 is a section on the line 11—11 of 70 Fig. 5; and

Fig. 12 is a section on the line 12—12 of Fig. 11.

Referring now to the drawings in detail, the receptacle shown comprises a two-part insulating base, the lower portion 20 of 75 which carries the contacts, binding-terminals, and switch mechanism, and the upper part 21 of which serves as a cover or housing for the parts supported by the lower part 20; an oscillatively-mounted shell contact 22 swiveled on the lower base 20, a center contact 23 the connections for which form the pivot for the oscillating shell contact, a double-pole snap-switch mechanism 24 operated by the oscillation of the shell 80 contact 22, binding-terminals 25 and 26 for the center and shell contacts, respectively, and a receptacle portion 27 for the reception of the blades of a quick-detachable connector device. 85

The binding-terminal 25 is electrically connected with a spring switch contact or brush 28, which is connected with the center contact when the switch is in "on" position; and the binding-terminal 26 is electrically 90 connected with a spring switch contact or brush 29, which is electrically connected with the shell contact when the switch is in "on" position.

The center contact 23 (Fig. 5) comprises 100 a metal disk riveted to the upper end of a post 291, which post forms the pivot for the oscillative shell contact 22, and is securely fastened to the lower base portion 20 105 by means of a nut 30 threaded onto the lower end of the post. This post 291 is formed of conducting material, and a contact or brush 31 is electrically connected

therewith and extends outwardly to a position opposite the brush 28, so that when the switch is in "on" position it completes the circuit from the brush 28 to the brush 31 and thence to the center contact 23 through the post 291.

The post 291 extends through an opening in the spring contact 31 and is provided with an enlarged portion 32, which forms a bearing or pivot for an oscillating switch member and also serves as a shoulder to clamp the spring contact 31 firmly in position on the base portion 20.

In order to pivotally mount the shell contact 22 on the post 291, the flange 321 of the shell contact is clamped between insulating disks 33, 34 of fiber or other suitable material, these disks being pierced to receive the post 291, the flange 321 itself being provided with an opening considerably larger than the pivot-post, so that it is insulated from the latter.

The disks 33, 34 may be secured to the flange in any suitable manner, as by eyelets 25 extending through registering openings in the disk and flange.

The threaded shell contact 22 is provided with a lamp-base gripping device which is carried by the threaded shell and the insulating disk 34. This lamp-base gripping device is in the form of a wire spring having a U-shaped portion 36 which embraces the threaded contact and extends into slots 37 located on opposite sides of the threaded shell contact, into engagement with the threaded lamp-base. The ends 371 of the spring lamp-grip are bent to extend alongside of the threaded shell contact and are inserted in openings in the disk 34 to assist in holding the spring in place.

The engagement of the U-shaped portion 36 with the slots in the threaded shell, and the engagement of the portions 371 with the disk 34 securely hold the lamp-grip device in place.

Before describing the manner in which the threaded shell contact is brought into the circuit when the switch mechanism is in "on" position, it will be necessary to describe the construction of the switch mechanism itself.

This switch mechanism comprises an insulating oscillative contact-carrying member 38 mounted on the enlarged portion 32 of the post 291, a link 39 of conducting material having a sliding engagement with a contact and conducting member 40 (this member 40 being secured to the oscillative member 38), a coil compression spring 41 surrounding the link 39 and bearing on the shoulder 42 of the link, and a crank-pin 43 of conducting material firmly secured to the flange 321 of the threaded shell contact 22.

The member 40 comprises a contact and conducting portion 44 lying along the upper

face of the oscillative member 38 and movable into position to engage the spring contact 29 when the switch is in "on" position. Thus, when the switch is in "on" position, the shell contact 22 is electrically connected 70 with the spring contact 29 through the member 44, the link 39, and the crank-pin 43.

The member 44 may be a sheet-metal stamping having a U-shaped portion (Fig. 12) embracing the member 38 and having 75 portions 45 indented into corresponding depressions in the member 38.

The link 39 and spring 41 operate in a triangular opening in the member 38, a portion 46 of the member 44 being bent to 80 extend into this triangular opening and having an opening in which the end of the link 39 is slidably mounted.

In addition to carrying the contact 44 which engages the spring contact 29, the 85 insulating member 38 also carries a contact and conducting member 47, which embraces the member 38 and bridges the gap between the contacts 28 and 31 when the switch is in "on" position.

The oscillating movement of the threaded shell contact 22 may be limited by means of stop shoulders 48 and 49 (Fig. 2), which are positioned to engage portions of the straight edge 50 of the insulating disk 34 when the 95 latter is operated in one direction or the other.

The relative oscillating movement between the threaded shell contact 22 and the insulating member 38 may be limited by the engagement of the crank-pin 43 with the edges of the triangular opening in which the link 39 operates (Fig. 11).

The binding-terminals 25 and 26 are electrically connected to the spring contacts 28 105 and 29, respectively, by means of screws 51, 52, which also serve to hold the binding-terminals 25 and 26 in position on the upper base 21, and also serve to hold the upper base 21 in position on the lower base 20. 110

The spring contacts 28 and 29 are held in place on the lower base 20 by means of eyelets 53, through which the screws 51 and 52 extend.

Conducting strips 54 extend from the eyelets 53 over to the contacts 55 of the quick-detachable receptacle portion 27.

The use and operation of our improved device is as follows: The device is wired by connecting the two feed-wires to the binding-terminals 25 and 26, respectively. The binding-terminal 25 is electrically connected with the spring contact 28 through the screw 51, and the binding-terminal 26 is electrically connected with the spring contact 29 through the screw 52. The contacts 28 and 29 thus are live parts when the device is wired.

Assuming that the switch is in "off" position and there is no lamp or plug in the re- 120 125 130

ceptacle and it is desired to place a lamp in the socket, the lamp is brought into position and screwed into the receptacle in the usual manner. As the lamp-base is screwed

5 in, its frictional engagement with the shell receptacle 22 and the lamp-grip 36, causes the shell 22 to oscillate on the post 291.

At a certain point in the oscillation of the shell contact 22, the switch snaps to "on"

10 position. This certain point in the oscillation is after the pivot-pin or crank-pin 43 has passed the dead center between the post 291 and the sliding connection between the link 39 and the portion 46 of the member

15 40. After this dead center is passed, the tension in the spring 41 tends to snap the shell contact 22 in one direction and the oscillative insulating member 38 in the other direction. This snap action of the oscillative member 38 snaps the contact member 47

20 into position between the spring contacts 28 and 31 to bring the center contact 23 into the circuit, and snaps the contact member 40 into engagement with the contact 29 to bring the shell contact into the circuit.

When the lamp is unscrewed from the socket the reverse operation of the switch mechanism takes place. The frictional engagement of the lamp-base with the screw shell contact 22 and the lamp-grip 36 causes the screw shell to oscillate and causes a snap action of the switch mechanism to "off" position. This snap action takes place after the pivot-pin 43 passes the dead center position. The screwing out of the lamp-base thus leaves the switch in "off" position and leaves both contacts of the receptacle dead.

We claim as new and desire to secure by Letters Patent of the United States:

40 1. An electrical receptacle comprising a center contact, a pivotally-mounted shell contact, a gripping device for the inserted device carried by said shell contact, a movable switch-arm, a switch spring means whereby one of its ends is moved back and forth by the movement of the shell contact and means whereby the movement of said spring throws said switch arm back and forth to make and break the circuit through the inserted device.

45 2. An electrical receptacle comprising a center contact, a shell contact arranged to receive a translating device and mounted to have limited turning movement in opposite directions, switch mechanism for opening and closing the circuit, said mechanism including a spring arranged to operate said switch mechanism with a snap action, and means connecting said shell contact with said spring, whereby said switch mechanism

acts to open or close the circuit as said shell contact is turned in one direction or the other.

3. An electrical receptacle comprising a center contact, a pivotally-mounted shell contact, and a switch operated by said shell contact for controlling the circuit through both of said contacts.

4. An electrical receptacle comprising a center contact, a shell contact, and a double-pole switch operated by said shell contact for controlling the circuit through said center contact and the circuit through said shell contact.

5. An electrical receptacle comprising a pivoted contact, a switch-arm pivoted about the same axis as said contact, and means whereby oscillation of said contact in one direction causes oscillation of said switch-arm in the opposite direction.

6. An electrical receptacle comprising a center contact, a pivotally-mounted shell contact, a switch-arm, and a link having a pivotal connection with said shell contact and a sliding connection with said switch-arm.

7. An electrical receptacle comprising a center contact, a shell contact, a pivotally-mounted insulating disk carrying to said shell contact, and a lamp-grip member comprising a U-shaped portion embracing said threaded shell contact and having a portion alongside said threaded shell contact and secured to said insulating disk.

8. An electrical receptacle comprising a shell contact mounted to oscillate in opposite directions about its longitudinal axis, a switch comprising a movable blade, contacts arranged to be bridged by said blade, and spring means connecting said blade and said contact shell for moving said blade into and out of contact with said switch contacts when said shell is oscillated.

9. An electrical receptacle comprising a shell to receive a translating device, said shell being mounted to oscillate in opposite directions about its longitudinal axis, a switch mechanism arranged for controlling the circuit through the contacts of said receptacle, and means operatively connecting said shell with said switch mechanism, whereby movement of the shell in one direction will open the circuit and movement of the same in the opposite direction will close the circuit.

In witness whereof, we have hereunto subscribed our names.

REUBEN B. BENJAMIN.
W. A. ALDEN.
